United States Patent Office

Des. 208,948
Patented Oct. 17, 1967

208,948

GUITAR

Thomas W. Jennings, Bexleyheath, Kent, England, assignor to Warwick Electronics Inc., Chicago, Ill., a corporation of Delaware

Filed June 27, 1966, Ser. No. 2,819

Term of patent 14 years

(Cl. D56—1)

FIG. 1 is a top plan view of the guitar, showing my new design;

FIG. 2 is a side elevational view;

FIG. 3 is an end elevational view; and

FIG. 4 is a bottom plan view thereof.

I claim:

The ornamental design for a guitar, as shown.
